Franklin D. Shoup

Attorney

UNITED STATES PATENT OFFICE.

WILLIAM W. HOLMAN, OF WASHINGTON, DISTRICT OF COLUMBIA.

IDENTIFICATION HATBAND.

Application filed October 16, 1922, Serial No. 594,772. Renewed August 21, 1923.

To all whom it may concern:

Be it known that I, WILLIAM W. HOLMAN, a citizen of the United States, residing at Washington, in the District of Columbia, ⁵ have invented certain new and useful Improvements in Identification Hatbands; and I do hereby declare the following to be a full, clear, and exact description of the invention, such as will enable others skilled in the art ¹⁰ to which it appertains to make and use the same, reference being had to the accompanying drawings, and to the letters and figures of reference marked thereon, which form a part of this specification.

¹⁵ This invention relates to identification tag holders with especial reference to means for maintaining the identification tag in a hat, and has for an object to provide improved means for connecting an identification tag with the sweat-band of a hat whereby identification data may be disclosed through a sight opening in the sweat-band.

²⁰ A further object of the invention is to provide a sweat-band having a sight opening with a waterproof transparent sheet covering said sight opening and with improved means at the reverse side of said sweat-band for maintaining an identification tag in proper relation to the sight opening and ²⁵ ³⁰ protected by the water-proof transparent sheet.

³⁵ A further object of the invention is to provide improved means for maintaining the identifying device in proper conjunction and relation with the sweat leather of a hat.

With these and other objects in view the invention comprises certain novel parts, elements, units, combinations, constructions and functions, as disclosed in the drawings, together with mechanical equivalents thereof, ⁴⁰ as will be hereinafter more fully described and claimed.

In the drawings:

⁴⁵ Figure 1 is a perspective view of a hat seen from below disclosing the identifying data through a sight opening in the sweat leather;

Figure 2 is a view of the reverse side of the sweat leather showing the identification device thereon and carried thereby, partly in elevation and with parts broken away;

⁵⁰ Figure 3 is a transverse sectional view through the device and the sweat leather taken on line 3—3 of Figure 2 and on an ⁵⁵ enlarged scale;

Figure 4 is a perspective view of the trans-

parent member here shown as of curved formation, although such curvature will be merely its position in use, its unattached shape being that substantially of a plane. ⁶⁰

Like characters of reference indicate corresponding parts throughout the several views.

It is a well recognized fact that in places where a considerable number of hats are ⁶⁵ deposited, confusion results from the general similarity and owners oftentimes unintentionally carry away hats not their own. The present invention is intended to provide means for complete identification of a hat so ⁷⁰ that in case it is carried away by one not its rightful owner it may be returned to the rightful owner without difficulty. The identification as provided in this invention is intended to replace the use of initials or other ⁷⁵ incomplete identifying data and to enable the holder of a hat to at once identify the rightful owner in case of misappropriation.

For the purpose the usual and ordinary sweat band or its substantial equivalent, ⁸⁰ indicated at 10, usually constructed of leather or leather-like material, is provided with an opening therethrough indicated at 11. The usual sweat-band is constructed with a piping 12 composed of a separate sheet of ⁸⁵ material usually thinner than the material of the sweat leather and in many, in fact most cases, secured to the sweat leather by means of zig-zag stitching 13. In the making up of the sweat-band it is the intention of the present invention to insert between the inner flap 14 of this piping and the sweat leather a transparent member 15, preferably in the present state of the art consisting of a sheet of flexible celluloid or similar flexible transparent material. The edge of this sheet is inserted between the flap 14 and the sweat leather, as noted and one row of the zig-zag stitching is stitched through the edge of the transparent member, as indicated at 16. ⁹⁰ ⁹⁵

A stitching 17 is also provided around adjacent to the margin of the opening 11 in the sweat leather, whereby the edges are prevented from curling or otherwise becoming objectionable and also assisting in maintaining the transparent sheet 15 in position. ¹⁰⁰

In the making of the transparent sheet 15 the ends are preferably folded upon themselves, as indicated at 18 forming guides for ¹⁰⁵ positioning the card 19 which carries the identifying data, thereby disclosed through ¹¹⁰

the sight opening and through the transparent sheet. Preferably these turned ends 18 will stop short of the bottom, as indicated at 20 in Figure 4, to correspond as 5 nearly as possible to the thickness of the piping strip 12.

To maintain the identifying card 19 against accidental displacement some form of catch is provided, one form being produced by stamping out at 21 (see Fig. 3) a tongue 22 which may be inset sufficiently so that the card will catch under this tongue 22 and prevent accidental displacement. At Figure 4 one of these tongues at 22 is shown intermediate the ends of the sheet, while at Figure 2, two of the tongues are shown. It is to be understood that the number of such tongues is not essential to the present invention and that any number may be employed as circumstances may make necessary or desirable.

In use it will be obvious that the transparent member 15 will be secured upon the reverse side of the sweat leather covering 25 the sight opening 11 by means of stitching, although it is obvious that any other means of securing it in position will be fully within the present invention. The transparent sheet, as above noted, is of water-proof material so that the efficiency of the sweat leather is not lessened by the formation of 30 the sight opening. The water-proof condition of this sheet also protects the card 19 which may be of ordinary card-board or any

other material found desirable and the name of the owner of the hat may be printed, written, stamped or otherwise applied to this card to be visible through the opening. When so properly marked the card will be placed in position by sliding under the 40 turned ends 18 until it passes under the tongues 22, whereupon it is held against accidental displacement and a continual identification of the hat.

What I claim is:

1. A hat identifying means comprising a sweat leather having a sight opening cut therethrough, a transparent flexible sheet secured to the reverse side of the sweat leather and covering the sight opening, and means 50 carried by the transparent sheet for maintaining an identifying card in position for inspection through the sight opening.

2. A hat identifying means comprising a sweat leather having a sight opening therethrough, a transparent sheet secured to the reverse side of the sweat leather and covering the sight opening, said transparent sheet having inwardly turned ends forming guides, a card carrying identifying data inserted into the guides and disclosed through the sight opening, and locks formed upon and integral with the transparent sheet for maintaining the card in position.

In testimony whereof I hereunto affix my 65 signature.

WILLIAM W. HOLMAN.
